UNITED STATES PATENT OFFICE.

QUAY C. BARBER, OF CLEVELAND, OHIO.

PEENING TOOL.

Application filed June 18, 1927. Serial No. 199,773.

The present invention is directed to improvements in peening tools.

The primary object of the invention is to provide a tool of this character so constructed that it can be inserted in the bore of a gas or steam engine cylinder in order that the metal will be subjected to a series of blows to impart thereto a harder scleroscope reading and, consequently, a harder wearing surface.

Another object of the invention is to provide a tool of this kind so constructed that it can be gradually lowered in the bore of a cylinder and rotated in order that the inner wall of the cylinder bore will be subjected to the action of the peening head.

In the accompanying drawings:

Figure 1 is a side elevation of the tool showing the same in connection with the bore of a cylinder.

Figure 2 is an enlarged detail sectional view through the head and sleeve.

Figure 3 is a sectional view on line 3—3 of Figure 2.

Figure 4 is a detail sectional view through the hose connection.

Referring to the drawings, the numeral 1 designates a sleeve which is fixed in any suitable manner to the front head 2 of a pneumatic tool 3 of any well known type, the piston hammer 4 of which is reciprocated in the usual manner. In order that the piston hammer may be reciprocated, a spindle 5 is threaded into the back head 6 of the tool, said spindle having an axial bore 7 and a transverse passage 8 in order that compressed air can be conducted to the tool for reciprocating the hammer. A collar 9 is rotatably engaged upon the spindle and has an annular chamber 10 formed therein to permit air from the nipple 11 to enter the passage 8, bore 7, and thence into the piston hammer chamber of the tool 3.

An air hose 10' is connected to the nipple 11 and leads from any suitable source of supply of compressed air. The upper end of the spindle 5 is designed to engage in the chuck of a drill press in order to rotate the tool 3, and since the collar 9 is swiveled thereon tangling of the hose 11 is obviously prevented.

The lower end of the sleeve 1 has formed integral therewith a head 12 provided with a conical chamber 13 and in which the lower end of the shank 14 extends, said shank be-

ing slidable in the sleeve 1 and having its upper end positioned to be subjected to the blows from the hammer 4. Mounted in the chamber 13 is a tappet 15 having a socket 16 and in which fits the extended end of the shank 14 as clearly shown in Figure 2 of the drawings.

The head 12 has bolted thereto a cap plate 16' formed with a central recess 17 and a plurality of radially disposed open-ended grooves 18, the bases of which being curved as at 19. Mounted in the grooves 18 for limited sliding movement are plates 20 having their outer ends provided with peening heads 21 and their inner ends provided with anvils 22, said plates having recesses 23 formed therein, the purpose of which will be later explained.

The inner edges of the plates are curved in order to conform to the curvature of the bases of the grooves. Coil springs 24 have their inner ends seated in the recesses 23 and their outer ends in engagement with a ring 25 clamped between the plate 16' and head 12, said springs normally serving to hold the peening heads 21 retracted within the grooves 18 and the anvils 22 above the plane of the upper surface of the plate 16'. The tappet is provided with an extension 26 which is seated in the recess 17 formed in the plate 16'.

In order that the stroke of the tappet may be regulated, set screws 27 are threaded in the head and are capable of having their inner ends impinged against the tappet 15. In operation, the spindle 5 is engaged in the chuck of a drill press or other suitable machine and the head 12 inserted in the bore of the cylinder 28, air for reciprocating the piston hammer 4 being admitted to the tool through the hose 10'. As soon as air is admitted to the tool the piston hammer during its reciprocation will strike the adjacent end of the shank 14, thus causing the tappet 15 to transmit the impact of blows to the anvils 22, whereupon the plates 20 will be rapidly vibrated in the grooves 18 in order that the peening heads 22 will strike the inner wall of the cylinder bore, the springs 24 serving to retract the plates after each blow. Since the head 12 is being rotated and gradually lowered by the drill press into the bore of the cylinder, the entire inner surface of the wall thereof will be subjected to the action of the peening heads.

Having thus described the invention, what is claimed is:

1. A tool of the class described comprising a head having radially disposed grooves 5 therein, plates slidable longitudinally in the grooves and having peening heads upon their outer ends and anvils upon their inner ends, a tappet in the head, a shank engaged with the tappet, and means for subjecting 10 the shank to the impact of blows for striking the anvils to actuate the peening heads.
2. A tool of the class described comprising a head having a plurality of radial grooves 15 therein, plates slidable in the grooves, the plates including anvils and peening heads, a tappet in the head for engaging the anvils to slide the plates, thereby operating the peening heads, a sleeve carried by the head, a shank slidable in the sleeve and having its 20 inner end engaged with the tappet, a motor

carried by the sleeve and having a piston hammer therein for striking the shank to impart movement to the tappet and thus to the plates.

3. A tool of the class described comprising 25 a head, a sleeve carried by the head, a motor carried by the sleeve, a shank in the sleeve, the motor having a piston hammer therein for striking the shank, said head having a plurality of radial grooves formed therein, 30 plates slidable in the grooves and having peening heads, resilient means for normally holding the peening heads retracted in the grooves, a tappet between the plates and shank for imparting blows to the plates when 35 the shank is subjected to blows from the piston hammer.

In testimony whereof I affix my signature.

QUAY C. BARBER. [L.S.]
